UNITED STATES PATENT OFFICE

160,863

GAME BOARD

Lewis J. Kalvig, Hackensack, Minn.

Application August 29, 1949, Serial No. 4,740

Term of patent 14 years

(Cl. D34—5)

To all whom it may concern:

Be it known that I, Lewis J. Kalvig, a citizen of the United States of America, residing at Hackensack, in the county of Cass, in the State of Minnesota, have invented a new, original, and ornamental Design for a Game Board, of which the following is a specification, reference being had to the accompanying drawing, forming a part thereof.

The single figure is a perspective view of a game board, showing my new design.

I claim:

The ornamental design for a game board, as shown.

LEWIS J. KALVIG.
